UNITED STATES PATENT OFFICE.

CHARLES N. TEETOR, OF HAGERSTOWN, INDIANA.

VALVE FOR INTERNAL-COMBUSTION ENGINES.

1,115,748.

Specification of Letters Patent.

Patented Nov. 3, 1914.

Application filed January 9, 1913. Serial No. 741,078.

To all whom it may concern:

Be it known that I, CHARLES N. TEETOR, a citizen of the United States, residing at Hagerstown, in the county of Wayne and State of Indiana, have invented certain new and useful Improvements in Valves for Internal-Combustion Engines; and I do hereby declare the following to be a full, clear, and exact description of the invention, such 10 as will enable others skilled in the art to which it appertains to make and use the same.

This invention is a valve for internal combustion engines more particularly adapted 15 to the four-cycle type, the primary object being to provide improved means for controlling the admission and exhaust of the engine gases.

A further object is to simplify the construction of the valve and render its operation positive and certain at all times, thereby preventing the faulty action of the controlling element by the accumulation of carbon, 20 burned oil, and the like.

25 A further purpose of the invention is to dispense with the usual flat valve seat and to provide a substantially cylindrical seat which accommodates both the intake and the exhaust.

30 Furthermore, the invention aims to produce a packing which is serviceable under all compressions; to provide a device in which it is unnecessary to depend on the absolute fitting of the parts, or oil-sealing; to provide 35 a controlling element which is adapted to close the intake during the compression, power and exhaust strokes; to insure the free movement of the gases both on the intake and exhaust strokes, and to so construct and 40 position the controlling element that it will be held in place by its own expansion when the same is free from engagement by the sleeve valve.

45 Other objects and advantages will become apparent from the detail description of the invention.

With these ends in view, the invention embodies a casing having intake and exhaust ports, a sleeve valve mounted for reciprocating movement within the casing, a controlling element positioned between the sleeve valve and the casing and in alinement with the intake and exhaust ports, and a piston 50 operating within the sleeve valve.

55 The invention consists, further, in the features of construction, the combination and arrangement of parts, as will be more

fully hereinafter set forth and pointed out in the appended claims.

One embodiment of the invention is illustrated in the accompanying drawings, but the construction shown therein is to be understood as illustrative, only, and not as defining the limits of the invention.

Figure 1 is a vertical sectional view, transverse of the crank shaft, of a portion of an engine showing the intake opening and exhaust closing. Fig. 2 is a fragmentary sectional view of the position of the parts with the intake open. Fig. 3 is a view similar to Fig. 2 illustrating the position of the parts as the intake closes. Fig. 4 is a similar view to Fig. 2 as the exhaust opens, with the sealing ring in operation. Fig. 5 is a view similar to Fig. 4 showing the exhaust open. Fig. 6 is an enlarged detail view of the controlling element, the sealing ring, and packing as illustrated in Fig. 2.

In the embodiment of the invention illustrated in the drawings, the casing 1 is shown 80 provided with the usual water jacket 2. Within the casing is positioned a sleeve valve 3 shown in the drawings as cylindrical in form and extending for a length substantially equal to the upper chamber of the 85 casing. This sleeve valve is mounted for reciprocating movement within the casing and is provided with a trunnion 4, serving as means for connecting the sleeve to suitable devices for the purpose of imparting reciprocating motion. Any preferred form of mechanism may be employed for accomplishing this result but in the drawings, I have shown a pitman 5 carried by an eccentric 6 mounted upon a shaft 7, which shaft is timed 90 to move at exactly one-half the crank shaft speed for an engine of the type disclosed. This shaft 7 may be rotated by any suitable means, from the driving shaft, such as gearing, not shown.

100 A piston 8 is mounted for reciprocating movement within the sleeve valve and this piston is provided with the usual or any preferred form of packing 9. The mechanism below the piston is indicated diagrammatically as this part of the engine is of the ordinary, or any preferred type.

110 The sleeve valve is shown of substantial thickness for a greater portion of its length except near the upper end thereof, where the outer wall is cut away to provide a chamber 10 which extends from a shoulder 11 to substantially the top of the sleeve, and this sleeve is also provided with a lower

channel 12 connecting with the chamber 10 and an upper channel 13 connecting with said chamber. The channel 12 is provided with the shoulders 11, 14 for the purpose to be hereinafter set forth. This chamber 10 and channels 12, 13 extend all the way around the sleeve valve in the preferred form of the invention. The sleeve valve is provided, also, with a port 15 which may be continued at intervals around the sleeve, if desired, as illustrated in Fig. 3. This port is adapted to coöperate with the intake port 16 of the casing 1. The casing is provided, also, with an exhaust port 17 shown in the drawings as positioned above the intake port 16.

The upper end of the sleeve valve 3 is provided with a packing ring 18 having a circumferential channel which is adapted to fit over a shoulder 19 of the sleeve valve. This packing ring 18 serves to close one end of the chamber 10. Another packing ring 20 is shown in the drawings as coöoperating with the ring 18, and this latter ring 20 is employed to seal the connecting joint of ring 18, by staggering the connections, as illustrated in dotted lines in Fig. 3, *a* indicating the end of the ring 18 and *b* indicating the end of ring 20, as will be understood by those skilled in the art. Connecting with the lower channel 12, is an oil groove 21 extending through the sleeve valve, which groove permits the oil in the chamber to form an oil packing for the parts.

An important feature of the invention is a controlling element 22, shown in the form of a sleeve having a shoulder or thickened portion 23 positioned within the channel 12 of the sleeve valve 3. This controlling element, or independent sleeve, is provided with a port 24 which is adapted to register with the intake port 16 and also with the port 15 of the sleeve valve when the controlling element is moved to a position with its shoulder 23 abutting against the wall 11. This controlling element is moved to its various positions by the shoulder 23 engaging wall 11 or wall 14 during the reciprocating movement of the sleeve valve 3 within the casing. However, it will be noted that the controlling element will be free from movement by the sleeve valve at certain periods of the stroke, at which time the controlling element will be held in position by its expansion. Coöoperating with this controlling element is a sealing ring 25 which is positioned in the channel 13 of the sleeve valve and carried by said valve. This sealing ring 25 operates to close the intake port 16 and the port 24 of the controlling element during the period when the exhaust port 17 is open, and permits said element to return to its lower position, for at this period of the stroke, the controlling element might be so positioned that it would not thoroughly

cut off the intake of material. The combined action, therefore, of the controlling element 22 and the sealing ring 25 operates to effectually control the passage of fuel through the intake port and thus save the gases. This feature of the invention will be more clearly understood by an examination of Figs. 3, 4 and 5, showing, respectively, the downward movement of the valve sleeve.

In operation, the engine as disclosed in Fig. 1 shows the piston up and the sleeve valve moving in position to uncover port 24 of the controlling element, bringing ports 15 and 24 into a position to admit the gases from the intake port 16 of the casing. As the piston moves down on the suction stroke, the sealing ring 25 entirely uncovers port 24 of the controlling element 22 and said element 22 is moved upward into complete alignment with the intake port 16 of the casing, as shown in Fig. 2, with the wall 11 of the sleeve valve coming into contact with the shoulder 23 of the controlling element. In Fig. 3, the intake port 16 is closed by the sleeve valve 3 pushing the controlling element 22 across said port 16. The piston is down ready for the compression stroke with the sleeve valve 3 in its highest position. It will be noted, also, that sealing ring 25 has closed the exhaust port 17. At this point, the sleeve valve 3 starts on its downward journey carrying the sealing ring 25 across port 24 of the controlling element, as shown in Fig. 4, making it impossible for the compressed gases and explosion to escape through the intake port. The further movement of the sleeve in this direction causes the wall 14 of the channel 12 to engage the circumferential shoulder 23 for the purpose of carrying the controlling element 22 across the intake port and downward to the exhaust position of the engine. In Fig. 5, the exhaust is shown entirely open and the sleeve valve 3 is disclosed at its lowest position. This figure also discloses the lowest position of the controlling element 22, wherein the intake port is effectually cut off by means of the sealing ring 25 coöperating with the controlling element 22. In the position of the parts disclosed in Fig. 4, it will be noted that the sealing ring 25 co-
operates with the controlling element 22 to cut off the intake port during the compression and explosion. From Fig. 1, it will be observed that the controlling element 22 is capable of being retained in position, independent of the action of the sleeve valve, said controlling element being held in place by its expansion.

Having thus described my invention, what I claim as new and desire to secure by Letters Patent, is:

1. In an internal combustion engine, a casing, a sleeve valve, and a freely movable port controlling element mounted between

the sleeve valve and the casing, said controlling element being actuated by the movement of said sleeve valve.

2. In an internal combustion engine, a casing having intake and exhaust ports, a sleeve valve, and a controlling element independently mounted between the sleeve valve and the casing, said controlling element being actuated by the movement of said sleeve valve, said controlling element being adapted for movement in the path of the intake and exhaust ports.

3. In an internal combustion engine, a casing having intake and exhaust ports, a sleeve valve having a chamber formed in the face thereof, and a controlling element adapted to assume various positions within said chamber and with reference to said ports irrespective of the sleeve valve.

20 4. In an internal combustion engine, a casing, a sleeve valve having a chamber, a piston within the sleeve valve, a crank shaft, a port controlling element within said chamber, and means moving at substantially one-half crank shaft speed for controlling the movement of the sleeve valve.

5. In an internal combustion engine, a casing, provided with intake and exhaust ports, a sleeve valve having a chamber formed in one face thereof, a controlling element positioned in said chamber and adapted to be moved with reference to said ports, and a sealing ring adapted to coöperate with the controlling element and one of said ports.

35 6. In an internal combustion engine, a casing provided with intake and exhaust ports, a sleeve valve having a chamber formed in one face thereof, a controlling element positioned in said chamber and adapted to be moved with reference to said ports, and a sealing ring in said chamber and carried by the sleeve valve, said sealing ring co-operating with the controlling element to close the intake port during the compression,

45 power and exhaust strokes.

7. In an internal combustion engine, a casing provided with intake and exhaust ports, a sleeve valve having a chamber formed in one face thereof, a packing ring and a sealing ring positioned in said chamber and carried by the sleeve valve, a controlling element independently mounted in said chamber, and means on said controlling element adapted to engage means on said sleeve valve whereby they may be moved in unison with reference to said ports in the casing.

8. In an internal combustion engine, a casing provided with intake and exhaust ports, a sleeve valve having a chamber formed in one face thereof and a port, abutting packing rings and a sealing ring mounted in the chamber and carried by

the sleeve valve, a controlling element in said chamber and having a port adapted to register with the ports of the valve sleeve and casing, and means whereby the controlling element and valve sleeve may be moved in unison with reference to the ports in the casing.

9. In an internal combustion engine, a casing provided with intake and exhaust ports, a sleeve valve having a chamber formed in one face thereof, a packing ring serving as an abutment at one end of said chamber, a sealing ring carried by the valve sleeve and of less thickness than said packing ring, a controlling element mounted in said chamber, and means on the controlling element to engage abutments on the sleeve whereby said controlling element may be moved to various positions by the sleeve valve.

10. In an internal combustion engine, a casing, a sleeve valve having a chamber and a channel between said sleeve and the casing, a controlling element positioned in said chamber and having a flange adapted to alternately engage the walls of said channel during the movement of the sleeve within the casing, a piston within the sleeve valve, and means for operating the sleeve valve independent of the movement of the piston.

11. In an internal combustion engine, a casing, a sleeve valve having a chamber and a channel between said sleeve and the casing, a controlling element positioned in said chamber and having a flange adapted to alternately engage the walls of said channel during the movement of the sleeve within the casing, an oil groove in said sleeve valve and connecting said channel, a plurality of packing rings closing one end of said chamber, a piston, and means for operating the sleeve valve independent of the piston.

12. In an internal combustion engine, a casing provided with intake and exhaust ports, a sleeve valve having a chamber and a port, a controlling element having a port, said controlling element being movable with reference to the ports of the casing and the sleeve valve, and a sealing ring in said chamber and carried by the sleeve valve, said sealing ring coöperating with the port of the controlling element and the intake port of the casing during the compression, power and exhaust strokes.

In testimony whereof, I affix my signature, in presence of two witnesses.
